UNITED STATES PATENT OFFICE

124,423

DESIGN FOR A LAVATORY WITH WATER HEATER

Le Roy A. Wilkinson, Aurora, Ill., assignor to The Showerway Company, Minneapolis, Minn., a corporation of Minnesota

Application December 20, 1939, Serial No. 89,030

Term of patent 14 years

To all whom it may concern:

Be it known that I, Le Roy A. Wilkinson, a citizen of the United States and residing in the city of Aurora, county of Kane, State of Illinois, have invented a new, original, and ornamental Design for Lavatory with Water Heater, of which the following is a specification, reference being had to the accompanying drawing, forming a part thereof, wherein—

Fig. 1 is a front perspective view of a lavatory with water heater, showing my new design,
Fig. 2 is a top plan view of the same, and
Fig. 3 is a side elevation of the same.

I claim:

The ornamental design for a lavatory with water heater, as shown.

LE ROY A. WILKINSON.
